DESIGN FOR SAFETY PAPER

Joseph Mehlman, Los Angeles, Calif.

Application February 6, 1939, Serial No. 82,800

Term of patent 14 years

To all whom it may concern:

Be it known that I, Joseph Mehlman, a citizen of the United States of America, residing at Los Angeles, county of Los Angeles and State of California, have invented a new, original, and ornamental Design for Safety Paper, of which the following is a specification, reference being had to the accompanying drawing, forming part thereof,

The figure of the drawing is a plan view of the safety paper embodying my design and including a complete design unit. The safety paper is especially adapted for use in the making of tickets for sports and athletic events.

I claim:

The ornamental design for safety paper, as shown and described.

JOSEPH MEHLMAN.
